UNITED STATES PATENT OFFICE.

DUFFA B. LAUZON, OF GRAND RAPIDS, MINNESOTA.

AUTOMOBILE-DOOR LATCH.

1,394,681.

Specification of Letters Patent. Patented Oct. 25, 1921.

Application filed June 9, 1920. Serial No. 387,659.

To all whom it may concern:

Be it known that I, DUFFA B. LAUZON, a citizen of the United States, and a resident of Grand Rapids, in the county of Itasca 5 and State of Minnesota, have invented certain new and useful Improvements in Automobile-Door Latches, of which the following is a specification.

This invention has reference to the class 10 of locks and latches, and more particularly to an improved latch and operating device therefor.

More especially, the invention has reference to an improved door latch for automobiles, the principal object of the device being to do away with the side motion in pushing the latch to open the same, thus permitting the opening of the door with one motion from the outside or the inside of 20 the car.

The invention further contemplates an improved and simple construction which obviates the protruding handle present on types of latches now employed, and using a laterally swinging lever disposed to operate in a plane parallel to the door, and which necessitates two distinct motions in the opening of the door, in addition to catching in one's clothing and being otherwise objectionable.

Other and further objects of my invention will become readily apparent to persons skilled in the art, from a consideration of the following description when taken in conjunction with the accompanying drawings, 35 wherein:

Figure 1 is a front elevation of my improved automobile door latch as applied to a door, the door being indicated in phantom, 40 and a portion of the latch being broken away to show the latch bolt,

Fig. 2 is an edge view of the latch, and

Fig. 3 is a horizontal sectional view taken on the line 3—3 of Fig. 1.

Referring to the drawings in detail, in which like reference characters indicate corresponding parts throughout the several views, my improved automobile door latch is shown as comprising a casing including 45 a front attaching plate 10 preferably of rectangular outline having one end 11 directed at right angles with respect thereto and each portion being formed with openings 12 for receiving screws or the like, in 50 order that the device may be secured in

position. Of course, it is to be understood that the device may be suitably positioned upon a door or other closure in connection with which it is used, but in accordance with the preferred embodiment of the invention, 60 the device is set within the door indicated at 13 so as to be practically hidden from view, the portion 11 being disposed at one edge of the door and otherwise, as will be hereinafter more fully described.

Mounted horizontally and longitudinally at the back of the plate 10 is a latch casing proper 14, preferably of rectangular cross section and comprising an open receptacle of sheet metal or the like, provided at its 70 edges with rivets 15 engaging corresponding slots in the front plate 10, in order that the device may be held in assembled relation. This casing is designed to receive a latch bolt 16 slidable therein and the angular end 75 portion 11 is provided with an opening 17 through which the reduced portion 18 of the bolt projects, said portion being beveled in the usual manner for coöperation with a keeper as is common in the art. This reduced formation produces shoulders 19 above and below, for engagement with the interior surface of the front wall 11, in order to limit the projection of the bolt under the action of an expansible helical 80 spring 20 which is mounted on a reduced and preferably circular extension 21 at the inner end of the latch bolt 16 and which is designed for free movement within the casing 14 sufficient to permit the bolt to be re- 85 tracted or projected. The reduced circular portion or shank 21 projects from the inner end of the latch bolt 16 medially of the width thereof and is engaged by the spring 20 which has one end disposed against the 90 inner end of the latch bolt and the other end disposed against the end wall 22 of the casing 14 in order to exert pressure tending to project the latch bolt in the manner shown in full lines in Fig. 3 of the drawings, 133 but adapted to permit retraction thereof in the manner shown in dotted lines in said view.

The bolt is further provided with a longitudinal slot 23 disposed to normally register with an opening 24 in the front portion 10 of the casing when the bolt is projected under the action of its spring, that is, at the inner end thereof, in which is rotatably mounted a roller or other anti-friction mem- 105 110

ber 25 upon a vertical pivot 26 suitably disposed through the top and bottom portions of the latch bolt. The outer end of the opening or slot 23 is disposed behind the front wall 10 except when the latch bolt is shifted to retract the same, as shown in dotted lines in Figure 3 of the drawings.

In order to permit the bolt to be retracted, and with a natural motion such as required 10 in opening the door, and in order to do away with the side motion in pushing the latch to open the same, in accordance with the present types of door latches, as used on automobile doors, so as to permit the opening 15 of the door with one motion instead of two or more, there is pivoted to the lower portion of the casing at the front portion 10, a lever or arm 27, the connection being of the usual hinge butt type. For this purpose, 20 the lower edge of the casing front is provided with spaced hinge butts or sleeves 28, which are turned up from the lower edge thereof and adapted to pivotally retain the lever or arm 27 therebetween through the 25 medium of a sleeve portion or butt 29 in conjunction with a pivot pin or pintle 30, thus permitting pivotal movement of the lever in a limited arc, restrained beneath a stop member or guard 31, which is suitably 30 riveted or otherwise secured to the front portion of the case.

Also, as illustrated, the lever is directed upwardly and outwardly at its lower portion, and its upper portion extends vertically at an obtuse angle with respect thereto, 35 the upper end being formed with or having secured thereto, a gripping portion or handle 32 of hard rubber, metal or otherwise suitably formed. As shown, the upper end of 40 the strip forming the lever 27, which is of sufficiently heavy sheet metal, is provided with a cross arm or opposite extensions 33 to which is detachably secured the hard rubber handle or gripping portion 32 preferably 45 of arcuate formation with the concaved edge thereof disposed uppermost and the convex edge thereof disposed lowermost and tapered so as to operate in a slot 34 in the door 13, so that in addition to the latch bolt, 50 the handle or gripping portion is the only part of the device which projects without the door, and avoids unsightly appearance, while still producing a latch of practical operating features and durability of construction and design. The gripping portion or 55 handle 32 is provided with a series of depressions or hollowed out finger seats 35 to receive and prevent slipping of the fingers when applied to open the door by retracting 60 the bolt due to a transverse movement of the lever with respect to the thickness of the door instead of in a plane parallel to the door and side of the car. The lower portion 27 of the lever is provided at its inner side 65 with a triangular or wedge shaped block 36

riveted or otherwise attached thereto or formed therewith, as indicated at 37 and disposed in juxtaposition to the slot 23 but normally disposed in engagement with the roller 25, whereby the normal projection of the bolt 70 under the action of the spring 20 will result in the lever being forced outwardly limited by the stop keeper or guard 31, by engagement of the roller 25 with the beveled or diagonal inner face of the block 36. However, when it is desired to retract the bolt 75 from the full line position shown in Figs. 1 and 2 of the drawings and also as shown in Fig. 3, to the dotted line position shown in Fig. 3 of the drawings, the lever is pressed 80 inwardly to cause the block 36 to act against the roller 25, thus shifting the bolt longitudinally against the action of the spring 20, the roller serving to reduce the friction between the parts. In this manner, the handle 82 85 may be actuated from the inside of the car or from the outside, by gripping over the top edge of the door 13 and depressing the handle and lever toward the outside of the car, the lever, upon being released, permitting the projection of the bolt of the latch automatically under the action of the 90 expansible spring 20 so that it will engage its keeper carried by the co-operating part of the side of the car or other suitable part, to 95 which the device is applied in use.

It will be seen that inasmuch as the handle is made to project through a slot in the door or closure, or from the side of the car body, in case the keeper is applied to the door, in 100 a reverse manner from that heretofore described, the rounding formation thereof, will prevent the projection of protruding parts such as would be likely to catch in one's clothing or result in the usual objections, especially to the ordinary form of latch employing a handle or lever having a side motion instead of a natural motion as required in opening the door. The gripping portion of the handle may be of hard rubber 105 or other suitable material and the depressions therein, serve to receive the fingers in such a manner as to insure that sufficient pressure may be exerted thereon and against the lever, in order to actuate the device to 110 retract the latch bolt. It will also be observed from Fig. 3 of the drawings, that the peak or tapered inner extremity of the angle of the block 36 comes in contact with the roller set in the groove or slot 23 in the latch 115 bolt and when the lever is operated so that the base of the angle is disposed against the roller, the latch bolt will be retracted to clear the keeper whereby the door may be opened. When the door is closed, the keeper 120 will be automatically engaged by the latch bolt, due to the beveled formation of the latter, as is common in the art. The latch bolt is so fitted within its case, as to operate 125 with ease, sufficient clearance being allowed 130

on all four sides for this purpose. In this way, the employment of an extraordinary strong spring is obviated.

In view of the foregoing, it is thought 5 that the operation of the device will be readily understood and in view of the simplicity and practical value, that it will commend itself to those skilled in the art.

Having thus described my invention, what 10 I claim is:—

1. A door latch comprising a casing having an attaching plate, a bolt slideable in the casing, a spring normally projecting the bolt and adapted to permit retraction there- 15 of, and an operating lever pivotally carried by the plate and movably engageable with the latch bolt to retract the same by movement in a plane at right angles to the bolt and door, said lever being pivoted at its 20 lower end and being accommodated in the door.

2. A door latch comprising a casing having an attaching plate, a bolt slideable in the casing, a spring normally projecting the bolt and adapted to permit retraction there- 25 of, means to limit the projection of the bolt, said bolt having a longitudinal slot therein, a lever pivoted to the lower portion of the casing and plate and having a beveled block 30 for engagement in said slot, and an anti-friction member in the slot for contact by the beveled edge of the block whereby movement of the lever toward the bolt will retract the latter.

3. An automobile door latch comprising 35 an attaching plate having a portion at right angles thereto provided with a slot, a latch bolt having a reduced portion adapted to project through said slot, a casing for slid- 40 ably engaging said latch bolt, spring means tending to project said bolt and permitting retraction thereof, said bolt being provided with a longitudinal slot, an anti-friction member mounted in one end of said slot, a 45 lever pivoted to the lower portion of the plate, means carried by the plate to limit the

outward movement of the lever, said lever being provided with a triangular block projecting inwardly therefrom to engage said anti-friction member whereby movement of 50 the lever at right angles to the door will retract the bolt, said spring serving to project the bolt and move the lever outwardly when the latter is released, and a gripping portion on the lever.

4. An automobile door latch comprising the combination with a door having a casing mounted therein and provided with a slot at the inside; of a slideable latch bolt mounted in said casing, means normally projecting said bolt, the lower portion of the casing being provided with a pivot, an angular lever mounted on said pivot, means carried by the casing to limit movements of the lever away from the same, coöperating 60 anti-friction means between the lever and the latch bolt for retracting the bolt upon depression of the lever, and an arcuate handle at the upper end of the lever and fitted in the slot of the door to project there- 65 from and adapted to be depressed for re-tracting the bolt, said gripping portion being provided with finger depressions.

5. A door latch comprising a casing, a bolt slideable in the casing, means normally 70 projecting the bolt, and an operating lever pivotally carried by the casing and movably associated with the latch bolt to retract the same by movement in a plane at right angles to the path of movement of the bolt.

6. A latch of the class described comprising a casing, a bolt slideable in the casing, means urging the bolt into projected position, a lever pivoted adjacent to the bolt to swing at right angles to the movement direction thereof, said lever being pivoted in a plane parallel to the bolt, and means carried by the lever and operatively engaging the bolt upon repression of the lever in one direction on its pivot axis, said lever being 85 normally returned to its initial position.

DUFFA B. LAUZON.
